UNITED STATES PATENT OFFICE.

ANDREW J. SANFORD, OF NEWARK, OHIO, ASSIGNOR TO A. H. HEISEY & CO., OF NEWARK, OHIO.

DESIGN FOR A BOWL.

45,127.

Specification for Design.

Patented Jan. 6, 1914.

Application filed October 29, 1913. Serial No. 798,149. Term of patent 14 years.

To all whom it may concern:

Be it known that I, ANDREW JOHN SANFORD, a citizen of the United States, residing at Newark, Ohio, have invented a new, original, and ornamental Design for a Bowl, of which the following is a specification, reference being had to the accompanying drawing, forming part thereof.

Figure 1 is a side elevation of a bowl embodying my design, and Fig. 2 is a bottom plan of the same.

I claim:

The ornamental design for a bowl, substantially as shown.

ANDREW J. SANFORD.
